(57) **CLAIM**

The ornamental design for a lighting device, as shown and described.

DESCRIPTION

FIG. 1 is a perspective view of the lighting device in accordance with our new design, the lighting device being in an expanded configuration;

FIG. 2 is a bottom view of the lighting device depicted in FIG. 1 in its expanded configuration;

FIG. 3 is a front view of the lighting device depicted in FIG. 1 in its expanded configuration;

FIG. 4 is a back view of the lighting device depicted in FIG. 1 in its expanded configuration;

FIG. 5 is a left side view of the lighting device depicted in FIG. 1 in its expanded configuration;

FIG. 6 is a right side view of the lighting device depicted in FIG. 1 in its expanded configuration;

FIG. 7 is a perspective view of the lighting device in a collapsed configuration;

FIG. 8 is a bottom view of the lighting device in its collapsed configuration;

FIG. 9 is a front view of the lighting device in its collapsed configuration;

FIG. 10 is a back view of the lighting device in its collapsed configuration;

FIG. 11 is a left side view of the lighting device in its collapsed configuration; and,

FIG. 12 is a right side view of the lighting device in its collapsed configuration.

The broken line forming a square around the claimed design is included for the purpose of illustrating environmental structure and forms no part of the claimed design.

The broken line forming a circular region within the claimed design defines the bounds of the claimed design and forms no part thereof.
